(57) **CLAIM**

The ornamental design for the controller for electronic device, as shown and described.

DESCRIPTION

FIG. 1 is a rear, top, left perspective view of the controller for electronic device showing our new design;

FIG. 2 is a front, top, left perspective view thereof;

FIG. 3 is a rear elevational view thereof; and,

FIG. 4 is a top plan view thereof.

The broken lines indicate the unclaimed portions of the controller for electronic device and form no part of the claimed design.

1 Claim, 4 Drawing Sheets*FIG. 1*

FIG. 2

FIG. 3

FIG. 4
